UNITED STATES PATENT OFFICE.

THOMAS J. BUNCH, OF HUGO, VIRGINIA.

CAR JOURNAL-BOX.

1,110,252.

Specification of Letters Patent.

Patented Sept. 8, 1914.

Application filed December 21, 1911. Serial No. 667,191.

To all whom it may concern:

Be it known that I, THOMAS J. BUNCH, a citizen of the United States, residing at Hugo, in the county of Southampton and State of Virginia, have invented certain new and useful Improvements in Car Journal-Boxes; and I do hereby declare the following to be a full, clear, and exact description of the invention, such as will enable others skilled in the art to which it appertains to make and use the same.

This invention relates to car axle boxes and has for an object to provide improved means for maintaining a brass therein.

With this end in view the invention comprises certain details hereinafter more fully described and claimed.

In the drawings:—Figure 1 is a perspective view of the improved box, a part of its top being broken away to show the interior construction. Fig. 2 is a transverse sectional view of the box on the line 2—2 of Fig. 1.

The improved box which forms the subject matter of this application is substantially in the usual and ordinary form, as indicated at 10, having an open front cut off oblique as indicated at Fig. 1 and closed by a closure 11 hinged thereto as at 12. At its end opposite the pivot the closure 11 is provided with a slot 13 adapted to engage a spring-pressed bolt 14 by which the closure is held normally closed but adapted to be readily opened when access to the box is required.

Within, the box is provided along its sides with tongues or ribs 15 adjacent the top of the chamber formed in said box, and a brass 16 is provided having grooves 17 formed therein proportioned and positioned along

its edges to fit upon the tongues 15 to hold such brass in position in the top of the box and to prevent its displacement therefrom under any extraordinary or accidental conditions. To prevent the withdrawal of the brass from the box a screw 18 is inserted through the side wall of said box into the path of movement of the brass and provided with a jam nut 19 which holds such screw in position. Heretofore similar screws have been inserted through the top of the box with their lower end passing over the front end of the brass; but I find that when the brass wears, the tip of the screw frequently scores or scratches the journal, or breaks or bends so that it is difficult of removal. By passing the screw through the side of the box its inner end or tip overlies the brass where the latter is thick and not subject to wear. The screw may have a head or nick 8 at its outer end, or any equivalent means for turning it. The jam nut is an advantage but not a necessity, though I prefer its use to prevent loss of the screw.

I claim:

A car journal box having an opening in its front, a closure for such opening, a brass within the box, tongue-and-groove connections between the sides of the box and edges of the brass, a screw passing removably inward through one side wall and one tongue of the box with its tip extending partway across and standing in front of the brass, and a jam nut on the screw outside the box.

In testimony whereof I affix my signature in presence of two witnesses.

THOMAS J. BUNCH.
